C. A. DIES,
ROTARY MOTOR,
APPLICATION FILED JULY 22, 1921.

Patented Oct. 31, 1922.

INVENTOR:

CHARLES A. DIES,

BY Robert A. Lewis, ATT'y.

Patented Oct. 31, 1922.

UNITED STATES PATENT OFFICE.

CHARLES A. DIES, OF CHICAGO, ILLINOIS.

ROTARY MOTOR.

Application filed July 22, 1921. Serial No. 486,678.

To all whom it may concern:

Be it known that I, CHARLES A. Dies, a citizen of the United States of America, and a resident of Chicago, in the county of Cook, 5 State of Illinois, have invented certain new and useful Improvements in Rotary Motors, of which the following is a specification.

This invention relates to portable rotary motors of the reversible type for use in connection with rotary tooth brushes and like 10 appliances, and has for its object:—

To provide a simple and efficient structural formation and association of parts in the motor unit whereby a reversal and stoppage of the same is readily effected, and with which a convenient inlet and outlet of the motive fluid is attained, all as will hereinafter more fully appear.

In the accompanying drawing:

20 Fig. 1, is a side elevation illustrating the general arrangement of parts in the invention.

Fig. 2, is an enlarged transverse section on line 2—2, Fig. 1.

25 Fig. 3, is an enlarged longitudinal section on line 3—3, Fig. 2.

Fig. 4, is a detail longitudinal section of a modification.

Like reference numerals indicate like 30 parts in the several views.

Referring to the drawing, 1 designates the motor casing formed with a circular bore or chamber for the rotary piston of the motor, and with a circular bore in parallel 35 relation to the piston bore for the reception of the semi-rotary controlling valve of the motor. In the preferred construction shown one end head 2 of the casing 1 is of a fixed or integral formation, while the companion 40 end head 3 is removable to admit of the assembly of the motor parts.

4 designates the rotary wheel or piston of the motor formed with a plurality of radial blades of any usual form, the outer 45 ends of which are adapted to revolve in adjacent relation to the inner circular face of the piston bore of the casing 1 aforesaid. Said wheel or piston 4 is carried on the end of a shaft 5 which has journal bearing in the fixed head 2 of the motor casing and in a central bearing sleeve 6 extending 50 axially from said head.

7 designates a semi-rotary valve member arranged in the valve bore of the casing 1 above described. Said valve member 55 is formed with a diametric passage 8 for

the motive fluid, with one end of said passage having communication with the bore of the hereinafter described tubular stem or handle, while the other end of said passage 8 is adapted for alternate registry with motor casing passages as follows:—

9 and 10 designate a pair of tangentially arranged passages connecting the above described piston and valve bores of the motor 65 casing 1 together, and adapted for alternate registry with the motive fluid passage 8 aforesaid, to direct the motive fluid to one side or the other of the wheel or piston 4 to cause the same to revolve in the direction 70 required. With the passage 8 moved to a position between the passage 9, 10 the supply of motive fluid is shut off and the motor comes to a stop.

11 designates the tubular stem or handle above referred to, fixedly attached to the valve member 7 and extending radially therefrom, with its bore or passage connecting with the aforesaid passage 8 of the valve member as shown. The stem 11 is formed 80 with an exterior adapted to receive and hold an end of a flexible tube or hose through which the supply of motive fluid is brought to the motor.

12 designates an elongated orifice in the 85 wall of the valve receiving bore of the motor casing 1, for the passage and movement of the stem 11 in the adjustment of the same and the associated valve member 7 in effecting the reversal and stoppage of the 90 motor above described.

13 designates a central sleeve or extension formed as a fixed part of the removable casing head 3 aforesaid, with the inner portion of its tubular bore adjacent to the wheel 95 or piston 4 formed with a flare 13' to afford a ready out flow of the motive fluid after its impelling action on said wheel or piston. The exterior of the sleeve 13 is formed to receive and hold the end of a flexible hose 100 adapted to conduct the waste motive fluid to a suitable point of discharge.

In the drawing the invention is shown as applied to a rotary tooth brushing appliance.

105

The modification illustrated in Fig. 4, differs from the arrangement of parts here-tofore described, in the formation of the brush carrying shaft 5' separate from the shaft 5 of the motor wheel or piston 4, and the connection of said shafts by a reducing 110 gearing, comprising a pinion 19 on the shaft

5 and an internal gear wheel 20 on the brush carrying shaft 5' as shown, or by any other suitable type of gearing generally used in effecting speed reduction.

5 Having thus fully described my invention, what I claim as new and desire to secure by Letters Patent, is:—

10 1. In a motor the combination of a motor casing formed with piston and valve chambers in parallel relation and connected together by a pair of tangential passages, a removable head closing one end of the piston chamber, a central tubular outlet neck on said head, a head closing the other end of the piston chamber, a central bearing sleeve on said head, a rotary piston of the radial bladed type arranged in said piston chamber, a shaft carrying said piston, journalled in the bearing sleeve aforesaid, a semi-rotary 15 valve member arranged in the valve chamber aforesaid and having a diametric passage, and a tubular inlet and operating stem 20

extending radially from said valve member.

2. In a motor the combination of a motor casing formed with piston and valve chambers in parallel relation and connected together by a pair of tangential passages, a removable head closing one end of the piston chamber, a central tubular outlet neck on said head having a flaring formation 25 towards the piston chamber, a head closing the other end of the piston chamber, a central bearing sleeve on said head, a rotary piston of the radial bladed type arranged in said piston chamber, a shaft carrying said piston journalled in the bearing sleeve aforesaid, a semi-rotary valve member arranged in the valve chamber aforesaid and having a diametric passage, and a tubular inlet and operating stem extending radially 30 from said valve member.

Signed at Chicago, Illinois, this 20th day of July, 1921.

CHARLES A. DIES.
